UNITED STATES PATENT OFFICE.

GEORGE M. THOMAS, OF PHILADELPHIA, PENNSYLVANIA.

CONSTANT-SURFACE-SPEED TALKING MACHINE.

Application filed January 11, 1926. Serial No. 80,412.

My invention, generally stated, relates to talking machines and have more especial relation to a novel, constant surface, speed mechanism for operating the turntable and record, as will be hereafter explained, whereby a record having a uniform length of sound wave will have imparted thereto an initial low speed at the outer edge of the record, for instance ten (10) revolutions per minute and which record will gradually have its speed increased to approximately seventy-eight (78) revolutions a minute, thereby appreciably increasing the length of playing surface over present types of constant revolution per minute records, which is one object of the present invention.

Another object consists in the provision of a novel construction of a swinging or floating arm, a turntable and its spindle carried thereby, a stationary tone arm having its sound box and stylus capable of vertical movement, and an electrically driven friction roller contacting with the turntable at a point below said stylus.

Still another object consists in the provision of a novel turntable actuating mechanism of the character above described, wherein the swinging arm carries a post for operating an electric switch for starting and stopping the motor at the proper periods.

A still further object of my present invention consists in the provision of novel details of construction, arrangement and combination of parts for attaining the results sought by the foregoing object.

The invention consists of the novel construction hereinafter described and finally claimed.

The nature, characteristic features and scope of the invention will be more fully understood from the following description taken in connection with the accompanying drawings forming part hereof, and in which:

Figure 1, represents a fragmentary view in plan of a talking machine construction embodying my invention.

Figure 2, represents a view in section taken upon the line 2-2 of Figure 1.

Figure 3, represents a view in section taken upon the line 3-3 of Figure 1.

Figure 4, represents a view in section taken upon the line 4-4 of Figure 1, showing the driving mechanism in a tilted position; and

Figure 5, represents a plan view of the swinging or floating arm in detached position.

For the purpose of illustrating my invention I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

Referring to the drawings in detail, the reference numeral 1 designates a conventional turntable such as is employed upon talking machines now in general use, made preferably of aluminum or other light material, and being mounted upon a swinging or floating arm 2 such, for instance, as is shown in Figure 5. The arm 2 which carries the turntable 1 is pivotally mounted at its rear end so as to be capable of both vertical and lateral movement. The turntable 1 is operated by an electric motor 4, (see Fig. 3) having a shaft 5, provided with a worm gear 6 for driving a worm wheel 7 mounted on the shaft 8, which is arranged at right angles to shaft 5, said shaft 8 having located thereon a spur gear 9 in mesh with another spur gear 10. The spur gear 10 is mounted on the shaft 11, which is parallel to the shaft 8 and carries the friction roller 12, which latter is in contact with the bottom of the turntable 1, for rotating the latter. The friction roller 12 is mounted directly beneath the sound box needle 13. The sound box 14 is pivotally mounted upon a stationary tone arm 15 having the goose neck 16. The turntable 1 has the lower portion of its vertical spindle 17 mounted in suitable ball bearings 18, carried by the upper and lower portions of the floating arm 2, which latter has its forward portion deflected upwardly and passing through the slot 19 of the motor board 20, the forward terminal having a finger piece 21 arranged for convenient manipulation of the arm and its adjuncts, so that the same may be manually moved from the position seen in dotted lines in Figure 1, to the position shown by full lines. The arm 2 is moved in one direction

by the action of the needle of the sound box in the spiral grooves of the record and is returned to its original and supporting position by hand subsequent to the lifting of the sound box. The rear end of the floating arm 2 is pivotally mounted on the pin 22, which is carried by the block 23, having the rear vertical hole 24 therein. The block 23 is seated in a recess 25 in the bracket 26, in which is the vertically disposed pin 27, which passes through the hole 24 in the block 23. It will thus be seen that the arm 2 is capable of movement vertically in an arc of a circle upon the pin 22, and its proper position is assured by the adjusting screw 28, seen in Figures 2 and 5. The arm 2 and the rear block 23 move laterally, in an arc of a circle as a unit, upon the vertical pivot pin 27, and the extent of such lateral movement is limited by the opposed adjusting screws 29, seen in Figures 1 and 2. Adjacent the rear portion of the arm 2 there is provided a pendant post 30, which alternately contacts with the opposed arms 31 and 32 of the electric switch 33, which may be of any conventional type. The records 34 are made with an accurately located center hole, having a bushing therein, if necessary. 35 designates a suitable switch for throwing off the electric current, when the machine is not in use. It is believed that from the foregoing detailed description, the operation of my novel talking machine structure will be readily understood. However, 35 it may be stated that according to my present invention, with the motor 4 operating, the disc record 34 is revolved first at low speed, say ten revolutions per minute which speed is gradually increased to say seventy-eight revolutions per minute and during such operation several times the amount of playing surface of the record 34 is afforded over conventional types of talking machines with a constant, uniform rate of speed revolution. 45 Also the novel feature of electric switch for starting the motor and stopping the same forms an important point in the operation, particularly since an initial adjustment of said switch serves to cause stoppage of all records, at approximately the same position. The adjustment of the electric switch is secured by suitable adjustment of set screws in the hubs of each of the switch arms. 50 Another feature in the operation is that when desired the floating arm 2 may be lifted vertically around its pivot point the advantages of which are apparent. The operation of the rotating disc laterally with respect to the stationary tone tube also forms 55 a novel feature and in so far as I am advised comprises a new movement in talking machine operation.

It will now be apparent that I have devised a novel and useful construction of constant surface speed talking machine which

embodies the features of advantage enumerated as desirable in the statement of the invention and the above description and while I have in the present instance shown and described the preferred embodiment thereof which has been found in practice to give satisfactory and reliable results, it is to be understood that the same is susceptible of modification in various particulars without departing from the spirit or scope of the invention or sacrificing any of its advantages.

Having thus described my invention what I claim as new and desire to secure by Letters Patent, is:—

1. In a device of the character stated, a fixed tone arm including its sound box and needle, a laterally movable arm, a turntable rotatably mounted with respect thereto and movable laterally therewith, an electrical motor, friction means for driving said turntable, electrically operated means for driving said friction means, and electrically operated means for stopping rotation of said motor.

2. In a device of the character stated, a fixed tone arm including its sound box and needle, a laterally movable arm pivotally mounted so as to move vertically in an arc of a circle, a turntable rotatably mounted with respect thereto and movable laterally therewith, friction means for driving said turntable an electrical motor, electrically operated means for driving said friction means, and electrically operated means for stopping rotation of said motor.

3. In a device of the character stated, a fixed tone arm including its sound box and needle, a laterally movable arm, a turntable rotatably mounted with respect thereto and movable laterally therewith, friction means for driving said turntable, electrically operated means including a motor and a train of gear wheels for driving said friction means, and electrically operated means for stopping rotation of said motor.

4. In a device of the character stated, a fixed tone arm including its sound box and needle, a laterally movable arm, a turntable rotatably mounted upon ball bearings with respect thereto and movable laterally therewith, an electrical motor, friction means for driving said turntable, electrically operated means for driving said friction means, and electrically operated means for stopping rotation of said motor.

5. In a device of the character stated, a fixed tone arm including its sound box and needle, a laterally movable arm, a turntable rotatably mounted with respect thereto and movable laterally therewith, an electrical motor friction means for driving said turntable, electrically operated means for driving said friction means, and electrically operated means including an electric switch

having a fixed arm in the path of travel of said movable arm for stopping rotation of said motor.

6. In a device of the character stated, a fixed tone arm including its sound box and needle, a laterally movable arm, a turntable rotatably mounted with respect thereto and movable laterally therewith, an electrical motor, friction means for driving said turn-

table, electrically operated means for driving 10 said friction means, and electrically operated means for stopping rotation of said motor, and a motor board having a slot therein through which slot said movable arm has movement.

In testimony whereof I have signed my name.

GEORGE M. THOMAS.
